CLAIM

The ornamental design for a marking press, as shown and described.

DESCRIPTION

FIG. 1 is a perspective view of a marking press showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the views are directed to environment and are for illustrative purposes only; the broken lines form no part of the claimed design.

In the drawings, the stippled shading represents surfaces having the contrast in appearance shown.

1 Claim, 5 Drawing Sheets
